(57) **CLAIM**

The ornamental design for a shopping bag as shown and described.

DESCRIPTION

FIG. 1 is a perspective view of a shopping bag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is another perspective view thereof; with the top of the shopping bag shown in an alternate position.

The broken lines in the drawings depict portions of the shopping bag that form no part of the claimed design.

1 Claim, 9 Drawing Sheets
